SPRING STRUCTURE

Vito Asaro, Detroit, Mich., assignor to L. A. Young Spring and Wire Corporation, Detroit, Mich., a corporation of Michigan

Application April 28, 1942, Serial No. 440,800

4 Claims. (Cl. 5—264)

This invention relates to improvements in spring structures.

The main objects of this invention are:

First, to provide an improved spring structure of the type in which the springs are mounted upon cross strips in which the cross strips may be fabricated of relatively light sheet metal stock, at the same time are very rigid and one to which the springs are easily and quickly secured.

Second, to provide a structure of this type in which the springs are or may be quickly and easily mounted upon and secured to the supporting strip or member in a manner that prevents loosening or rattling and at the same time holds the spring in upright position.

Third, to provide a structure having these advantages in which the springs can be assembled upon an associated supporting strip without the aid of tools.

Objects relating to details and economies of the invention will appear from the description to follow. The invention is defined and pointed out in the claims.

A preferred embodiment of the invention is illustrated in the accompanying drawing, in which:

Fig. 1 is a fragmentary perspective view of a supporting strip with a spring mounted thereon in accordance with my invention.

Fig. 2 is a fragmentary inverted view of the structure shown in Fig. 1.

Fig. 3 is a fragmentary longitudinal section on line 3—3 of Fig. 2.

Fig. 4 is a fragmentary inverted view corresponding to that of Fig. 2 showing certain steps of the mounting of the springs upon the support.

Fig. 5 is a fragmentary view showing the relation of the bottom coils of the spring prior to mounting upon the supporting strip.

In the accompanying drawing, I have only shown a fragment of a supporting strip and a single spring, but it will be understood that commonly the springs are mounted upon a supporting strip which is suitably conformed at its end for mounting upon a frame. As such mounting features are well known in the art and vary according to the type of structure in which the supporting strip and its springs are to be used I have not deemed it necessary to illustrate the same.

The supporting strip of my invention designated generally by the numeral 1 comprises a downwardly facing channel 2 and an upwardly facing channel 3, these channels having the common intermediate leg 4. The channel 2 is preferably substantially wider than the channel 3 to

provide an effective fit for the helically coiled spring 5 as will hereinafter appear.

The web 6 of the downwardly facing channel has a loop 7 struck up therefrom while the common leg 4 of the supporting strip has a somewhat elongated hole 8 therein, longitudinally spaced relative to the loop 7.

The bottom coil 9 of the spring terminates in a straight angularly disposed portion 10. This bottom coil 9 is threaded through the loop 7 and its terminal portion 10 is threaded through the hole 8 with the angle 11 thereof engaging the edge 12 of the hole adjacent the loop. This may be effected by a rotative or threading movement of the spring on its axis, the hole 8 being of such longitudinal dimension as to permit the tip of the terminal portion 10 to freely enter the hole. However, continued rotation of the spring brings the side 13 of the terminal portion into engagement with the edge 12 of the hole and under increasing stress as the rotation continues, so that the bottom coil is placed under spring stress. This relation of the parts is further illustrated in Fig. 4 where the tip terminal is about to enter the hole 8. The bottom coil is also under stress engagement with the outer leg 14 of the upwardly facing channel.

When the spring is completely seated, the tip of its terminal portion engages the outer leg 15 of the downwardly facing channel, see Fig. 2. The bottom coil is also placed under axial stress which brings the portion 16 thereof opposite the loop 7 in tension engagement with the top of the downwardly facing channel, see Figs. 1 and 3. Initially, the pitch of the bottom coil is substantially the same as that of the other coils, as shown in Fig. 5.

With this arrangement of parts, the springs may be very quickly mounted on the support and they are very securely retained against movement thereon and against any rattling or chafing and they may be engaged without the aid of tools and without excessive effort on the part of the workman as the workman can grasp the spring of the top coil, or well above the top coil and easily manipulate the spring to engage it with the support, as I have described.

I have illustrated and described my invention in an embodiment which I consider highly satisfactory. I have not attempted to illustrate or describe various embodiments or adaptations which I contemplate as it is believed that this disclosure will enable those skilled in the art to embody or adapt my improvements as may be desired.

Having thus described my invention, what I claim as new and desire to secure by Letters Patent, is:

1. In a spring structure, the combination of a supporting strip having a downwardly facing channel and an upwardly facing channel, the web of the downwardly facing channel having a loop struck up therefrom and the vertical leg common to said channels having a hole therein longitudinally spaced relative to said loop, and a helically coiled spring, the bottom coil of which terminates in a straight angularly disposed portion of a length corresponding approximately to the width of the downwardly facing channel, the bottom coil of the spring being threaded through said loop with its angularly disposed terminal portion disposed through said hole with its angle engaging the edge of the hole adjacent the loop under tension and its tip engaging the inner side of the outer leg of the downwardly facing channel, said bottom coil between said loop and hole also engaging the outer leg of the upwardly facing channel under tension, said bottom coil also being under axial stress whereby the spring is held in upright position with the portion thereof diametrically opposed to the portion engaging said loop under tension engagement with the top of the web of the downwardly facing channel.

2. In a spring structure, the combination of a supporting strip having a downwardly facing channel and an upwardly facing channel, the web of the downwardly facing channel having a loop struck up therefrom and the vertical leg common to said channels having a hole therein longitudinally spaced relative to said loop, and a helically coiled spring, the bottom coil of which terminates in an angularly disposed portion, the bottom coil of the spring being threaded through said loop with its angularly disposed terminal portion disposed through said hole with its angle engaging the edge of the hole adjacent the loop under tension, said bottom coil between said loop and hole also engaging the outer leg of the upwardly facing channel.

5 wardly facing channel under tension, said bottom coil also being under axial stress whereby the spring is held in upright position with the portion thereof diametrically opposed to the portion engaging said loop under tension engagement with the top of the web of the downwardly facing channel.

10 3. In a spring structure, the combination of a supporting strip having a downwardly facing channel and an upwardly facing channel, the web of the downwardly facing channel having a loop struck up therefrom and the vertical leg common to said channels having a hole therein longitudinally spaced relative to said loop, and a helically coiled spring, the bottom coil of which 15 terminates in a straight angularly disposed portion of a length corresponding approximately to the width of the downwardly facing channel, the bottom coil of the spring being threaded through said loop with its angularly disposed terminal portion disposed through said hole with its angle engaging the edge of the hole adjacent the loop and its tip engaging the inner side of the outer leg of the downwardly facing channel, said bottom coil between said loop and hole also engaging the outer leg of the upwardly facing channel.

20 4. In a spring structure, the combination of a supporting strip having a downwardly facing channel and an upwardly facing channel, the web of the downwardly facing channel having a loop struck up therefrom and the vertical leg common to said channels having a hole therein longitudinally spaced relative to said loop, and a helically coiled spring, the bottom coil of which 25 terminates in an angularly disposed portion, the bottom coil of the spring being threaded through said loop with its angularly disposed terminal portion disposed through said hole with its angle engaging the edge of the hole adjacent the loop, the portion of said bottom coil extending between said loop and hole also engaging under stress the outer leg of the upwardly facing channel.

VITO ASARO.
